UNITED STATES PATENT OFFICE.

PHILLIPS B. MARVIN, OF SOMERVILLE, MASSACHUSETTS, AND JOHN C. PHELAN, OF CHICAGO, ILLINOIS, ASSIGNEES TO INVISIBLE INK COMPANY, OF BOSTON, MASSACHUSETTS, A CORPORATION OF MASSACHUSETTS.

ATTACHMENT FOR REFRESHING TYPEWRITER-RIBBONS.

1,358,646.

Specification of Letters Patent.

Patented Nov. 9, 1920.

Application filed September 4, 1919. Serial No. 321,607.

To all whom it may concern:

Be it known that we, PHILLIPS B. MARVIN and JOHN C. PHELAN, citizens of the United States, residing, respectively, at Somerville, 5 in the county of Middlesex and State of Massachusetts, and Chicago, in the county of Cook and State of Illinois, have invented new and useful Improvements in Attachments for Refreshing Typewriter-Ribbons, 10 of which the following is a specification.

The object and purpose of this invention is to provide an attachment carrying a solvent for the inks used to impregnate typewriter ribbons, which attachment is 15 adapted to be applied upon the platen or cylinder of a visible-writing typewriting machine, in a position where the ribbon will be carried past it to receive a regulated quantity of the solvent. One useful result 20 or effect is that the ink in the zones near the edges of the ribbon is caused by the solvent to permeate the central zone, from which ink has been expelled to a greater or less extent by striking of the types; and another 25 effect is to preserve and increase the life of the ribbon, because the solvent used is of a somewhat oily nature, which keeps the fibers of the ribbon soft and pliant, and delays the wearing out of the ribbon by the abrasion 30 of the paper and types.

The invention is also intended for use for other machines, such as adding machines, addressing machines, etc., by which typed impressions are made with the use of an 35 inked ribbon. Therefore the term "type-writing machine" is used in this specification in a generic sense, typifying all machines using printing types and an inked ribbon to which the invention may be applied.

The reference above made to visible-writing typewriting machines is intended to mean machines of any sort using printing types and an inked ribbon, wherein the 40 ribbon is accessible to be engaged with a moistening device of the sort in which our invention is embodied when such device is applied upon an adjacent part of the machine.

50 In the drawings we have illustrated a preferred embodiment of our invention as adapted for use with a typewriting machine of the species commonly so called, and of the class in which the ribbon is at the front

side of the paper-supporting platen, this 55 being the class of machine commonly referred to as a typewriter with visible writing.

In said drawings:

Figure 1 is a perspective view of so much 60 of said typewriting machine as is necessary to illustrate the principle of our invention.

Fig. 2 is a side view of the device in which the invention is embodied, shown by 65 itself.

Fig. 3 is a longitudinal central section of the device.

Fig. 4 is a plan view.

Fig. 5 is a view of the pattern or blank from which the casing of the device is made. 70

Fig. 6 is a cross section of the device, made on an enlarged scale.

Like reference characters indicate the same parts in all of the figures.

Referring to Fig. 1, *a* represents the 75 paper-supporting cylindrical platen of one of the so-called visible-writing typewriting machines. *b* is the inked ribbon, and *c* is the drum on which the wound ribbon is held, and from which it is drawn to a drum 80 at the other side of the machine (not shown) when the machine is operated. Our ribbon refreshing device is detachably applied to a machine of this sort, and is provided with a clip *d*, adapted to be placed over the platen 85 *a*, and with a holder *e* for the solvent or solution by which the ribbon is treated.

Referring now to Figs. 2 to 6 inclusive for a detailed illustration, the clip *d* is shown as a flat strip of springy material, so 90 curved as to embrace a part of the platen and grip it, and one end of the clip is turned up and attached by soldering or otherwise to a guide *f*, having wings *f'* which embrace the holder *e*. This guide may be made of 95 sheet metal or any other sufficiently strong material, and the wings *f'* may be resilient, whereby to grip the holder yieldingly and permit the same to be adjusted without need of other fastening means.

The holder consists of a casing, in which there is placed a tank *g* for the solvent, a roller *h* for applying the solvent to the ribbon, and a wick *i* for conveying the solvent from the interior of the tank to the roller. The casing may be made of sheet material, such as sheet metal, sheet celluloid or other material, and we prefer to make it 105

- open at one end to permit of slipping the solvent tank endwise into it, and to form its sides so that they will hug the tank and hold it in place frictionally with spring 5 pressure, to provide lugs as *j* and *k* for the trunnions of the roller *h*, and to provide a guide for conducting the ribbon in contact with the surface of the roller but out of direct contact with the wick.
- 10 A pattern or blank, which we have found desirable for making out of one piece of material a casing having all of the features last mentioned, is shown in Fig. 5. This blank is adapted to be folded or bent on the dotted lines, and, after being so bent, the portion or panel *e*² forms the back, the panels *e*³ and *e*⁴ the opposite sides, *e*⁶ the top, and *e*⁷ the housing for the roller. The lugs *j* and *k*, which provide the bearings 15 for the roller, then lie across opposite ends of said housing. Two deep slots *l* and *m* are cut in the blank, between that part which forms the housing and the adjacent narrow zones or panels which form the 20 front of the casing. They are to receive and guide the ribbon. A notch *n* is cut in the upper end of the housing, and is flanked by points *o* and *p*; to make easier the passing of the ribbon through the slots and 25 around the outer side of the roller. As the lugs *j* and *k* are springy and resilient, the roller can be readily placed in its bearings by passing it through the open end of the casing, inserting one of the trunnions in 30 the bearing in the lug *j* and then springing the lugs apart far enough to admit the other trunnion to the bearing in lug *k* whereupon the lugs spring back and retain the roller.
- 35 The tank *g* may be made of sheet material, such as celluloid or sheet metal of any sort, or of glass or other molded or cast material. Preferably it is transparent; or at least that wall of it which is visible at the open end of the casing is transparent, whereby it is made possible for the user to know 40 how much of the solution remains in the tank. When it is finished it is leakage-tight, and has only one opening, this being 45 the slot *q*, through which the wick passes. The wick is bulky enough to pack the opening, preventing free escape of the solvent therefrom, and allowing only enough solvent to be drawn out by capillary attraction 50 to keep the exposed part of the wick moist. Likewise the wick is so tightly wedged in the opening that it can not be removed and replaced by the user, whereby refilling of the tank by the user is made impossible.
- 55 The wick bears against the surface of the roller *h*, and transfers a thin film of the solvent to it, when rotated by the ribbon.
- In use, the ribbon is placed between the roller and the walls of the housing, as 60 shown best in Fig. 6, and, being then wound

up on the drum *c*, it travels over the roller, rotating it, and receives a small amount of the solvent, this being the amount taken up by the roller as a thin film from the moist wick. The amount of solvent, although less than that which would either make the ink 70 run or the ribbon greasy, is yet enough to cause a flow of ink from the unused edge parts of the ribbon to the more or less exhausted middle part. Thus the supply of 75 ink in the used part is replenished.

When the solution in one tank becomes exhausted, that tank may be removed and a full one substituted. The fact that the casing is open at one end and that it retains 80 the tank only by the pressure of its sides makes it a very simple matter to remove an empty tank and substitute another. To start the tank, in removing it, we provide a hole *r* in the top wall of the casing, 85 through which a pencil point or any other convenient tool may be passed and caused to bear on the adjacent end of the tank.

The ribbon may be frequently treated in the manner described, and thereby kept in 90 a condition to make firm, clear impressions; that is, until the fabric is entirely worn out, the impressions may be substantially as bright and distinct as with a new ribbon; and the softening effect of the oily solution 95 results in diminishing the mechanical wear on the ribbon.

We claim as our invention and desire to protect any device having essentially the characteristics pointed out in the following 100 claims, without restriction to the machine on which it is used.

What we claim and desire to secure by Letters Patent is:

1. A device for refreshing typewriter ribbons, comprising a clip adapted to embrace a part of a typewriting machine, and having a guide, a holder contained in said guide and frictionally gripped by the sides of the latter, a tank for a solution, contained in 105 said holder and having a wick, and a roller rotatively mounted in the holder in contact with the wick and adapted to bear upon said holder and having a wick, and a roller 110 rotatively mounted in the holder in contact with the wick and adapted to bear upon an inked ribbon when the clip is applied to a part of the machine using such a ribbon. 115

2. A means for refreshing typewriter ribbons adapted to be applied to a typewriter embodying a holder, a tank for solution, detachably contained in said holder, a roller 120 rotatively mounted by the holder, a wick passing from the interior of said tank into contact with the surface of the roller, and a housing connected with the holder embracing the roller, there being guideways between said housing and the balance of the holder 125 to permit passage of the ribbon.

3. An inked ribbon refreshing device, comprising a tank for solvent having a slot, a wick passing through and filling said slot, a holder constructed as a casing embracing 130

said tank and having lugs, a roller supported by said lugs in contact with said wick, and ribbon-guiding means on the casing arranged to conduct an inked ribbon in 5 contact with the roller and out of contact with the wick.

4. An inked ribbon refreshing device, comprising a tank for solvent having a slot, a wick passing through and filling said slot, 10 a holder constructed as a casing embracing said tank and having lugs, a roller supported by said lugs in contact with said wick, and a clip shaped to embrace the platen of a typewriting machine and having a guide in 15 which said casing is held, whereby said device is applicable to machines of various types.

5. An inked ribbon refreshing device, comprising a casing having back and side 20 walls and a front housing and being open at one end, a solvent tank fitting between the side walls and being resiliently held thereby, a wick passing from the interior of the tank toward said housing, and a roller 25 mounted rotatably within the housing in surface contact with the wick; there being continuing openings at the sides and one end of the housing to admit a ribbon edgewise into contact with the opposite side of the 30 roller from the wick.

6. A refreshing attachment of the character described, comprising a casing, a tank containing solution removably held in said casing and having a transparent wall, which 35 wall is exposed to view from outside of the casing, whereby the content of solution in the tank may be observed, and means for

transferring solution from said tank to an inked ribbon passed adjacent to it.

7. In a device of the sort and for the purpose set forth, a casing having an open end and embracing side walls, a tank adapted to contain a typewriter-ribbon-refreshing solution fitting removably between said walls and having itself a transparent end wall exposed to view through the open end of the casing, and means for transferring solution from said tank to a typewriter ribbon traveling past it.

8. A refreshing attachment, comprising a 50 casing, a tank for solution, and means for transferring solution from said tank to an inked ribbon, the casing having walls adapted to bear frictionally upon the sides of the tank, and having an open end through 55 which the tank may be passed endwise, said casing having also an opening for admission of an instrument to push the tank outward from the open casing end.

9. A device for refreshing typewriter ribbons, comprising a holder, a tank for solution detachably held in said holder and having a slot, said tank being otherwise effectively closed, a wick passing through said slot and closing the same against leakage or 60 possibility of refilling, and a roller rotatively mounted on the holder and being in contact with said wick for transferring solution therefrom to a ribbon passing in contact with the roller. 70

In testimony whereof we have affixed our signatures.

PHILLIPS B. MARVIN.
JOHN C. PHELAN.
